FRANK BYCROFT KEALL, ALFRED HARRINGTON, AND RICHARD WILLIAM CHARLES BASSETT, OF LEICESTER, ENGLAND, ASSIGNEES, BY MESNE ASSIGNMENTS, TO UNITED SHOE MACHINERY CORPORATION, OF PATERSON, NEW JERSEY, A CORPORATION OF NEW JERSEY.

COMBINED EDGE-SETTING AND INDENTING DEVICE.

1,276,027.

Specification of Letters Patent. Patented Aug. 20, 1918.

Application filed November 27, 1914. Serial No. 874,240.

To all whom it may concern:

Be it known that we, FRANK B. KEALL, ALFRED HARRINGTON, and RICHARD W. C. BASSETT, subjects of the King of England, 5 residing at Leicester, Leicestershire, England, have invented certain Improvements in Combined Edge-Setting and Indenting Devices, of which the following description, 10 in connection with the accompanying drawings, is a specification, like reference characters on the drawings indicating like parts in the several figures.

This invention relates to edge setting machines of that type in which an iron for setting the sole edge is vibrated backward and forward along the length of the sole edge, and in which an indenting wheel is mounted 15 near the edge setting iron so that when the edge of the sole is pressed against the setting iron, the upper surface of the welt or sole is pressed against the under surface of the indenting wheel.

It has been proposed to mount the indenting wheel on a slide which allows the wheel 20 to move relatively to the edge setting iron, against the action of a spring, so as to adapt the wheel for indenting welts or corresponding parts of different widths, the form of indenting wheel usually employed being 25 frusto-conical, and the work being applied to it so that the upper is pressed against the base of the cone.

It is found, however, when using a device of this nature that since the pressure 30 applied to the wheel by the welt or equivalent part is almost perpendicular in direction to the line along which the slide must move, considerable friction results. The resulting stiffness of motion in the slide 35 causes damage to the upper through the undue pressure required between it and the base of the wheel, and also prevents the return motion of the wheel after it has been forced back from any cause during the edge 40 setting operation so that the upper surface of the welt or corresponding part of the shoe is not indented over its full width.

A further disadvantage of the combined edge setting and indenting devices at present in use is that they have only one edge setting surface above which the indenting wheel is centrally mounted. It is necessary 50 in such devices to cut away the upper cen-

tral portion of the edge setting surface, directly under the indenting wheel, in order to 55 position the wheel low enough to press properly on the upper surface of the welt or corresponding part of the shoe. The central portion of the edge setting face is its most important part in the setting operation, since the edge setting face is generally 60 convex about an axis substantially perpendicular to the tread face of the sole which is being operated upon and accordingly the maximum pressure occurs just where the 65 iron is cut away. The upper corner of the sole edge is therefore insufficiently set, since it is treated only by the portions of the tool on each side of the normal sole edge engaging portion of the iron. 70

A feature of this invention is a combined edge setting and indenting device comprising an improved organization in which the wheel has perfect freedom of movement to adapt itself to the width of the sole edge, 75 regardless of the pressure applied to it. Although this feature of the invention is shown in connection with a combined edge setting and indenting device, it should be understood that it may be useful in other 80 combinations, or may be used upon a machine for performing the indenting operation only.

Another feature of the invention comprises a combined edge setting iron and indenting device, in which the indenting wheel and the edge setting face of the iron are properly positioned to crowd the upper corner of the sole edge between them without interfering with the normal operation 90 of either one.

Other features of the invention will appear as the description proceeds.

In the accompanying drawings which illustrate one form of the invention: 95

Fig. 1 is a side view of the device, partly in section and partly broken away;

Fig. 2 is a front elevation;

Fig. 3 is a section on the line 3—3 of Fig. 1;

Fig. 4 is a perspective view of the setting iron with the indenting wheel removed;

Fig. 5 is an enlarged front elevation of an edge setting iron of ordinary construction;

Fig. 6 is a section on the line 6—6 of Fig. 4 showing the sole edge; 105

Fig. 7 is an enlarged front elevation of an edge setting iron improved in accordance with the present invention; and

Fig. 8 is a section on the line 8—8 of Fig. 6, showing the sole edge.

The body 1 is adapted to be mounted on a machine which will rapidly oscillate it transversely. It has fastened to it by the screw 2^a, a head 2 in which there is a vertical slot 3 having a filler block 4 mounted in the upper part of its front end by means of the pin 5 and screw 6. Slidably mounted in the slot 3 is the indenting wheel carrier 7, which fits closely laterally in the slot 3, but has some freedom of motion in other directions. It has two arms 8, 9 substantially at right angles, the arm 8 lying between the bottom of the slot 3 and the filler block 4, and the arm 9 lying between the filler block 4 and the rear vertical wall of the slot. The arm 9 has a recess 10 and the bottom face of the slot 3 has a substantially registering recess 11. A thrust pin or hinge member 12, having rounded ends, is mounted in small sockets in the inner ends of the recesses 10, 11. The pin 12 is smaller in cross-section than the recesses 10, 11 and therefore freedom for rocking motion of the arm 9 exists. The arm 8 and the filler block 4 have similar recesses 13, 14 respectively, in which a thrust pin or hinge member 15 is mounted. The arm 9 has a recess 16 in which there is a spring 17, the outer end of which bears against the vertical rear wall of the slot 3. The spring 17 tends to hold the arm 9 away from the rear wall of the slot 3, and in contact with the filler block 4, but when force is exerted against the base of the indenting wheel which is pivotally mounted at 19 upon the arm 8, the carrier 7 will swing back against the spring 17 on the pins 12, 15, which rock in the bearings at their ends. Thus rocking motion is substituted for sliding, and it is found in practice that no stiffness in the movement of the carrier 7 results from great upward pressure on the wheel 18, so that slight pressure of the upper against the base of the wheel 18 will move the carrier back, and conversely, the spring 17 will at all times hold the base of the wheel 18 in contact with the upper so that the whole of the upper welt or corresponding surface will be properly indented.

The edge setting iron 20 is mounted on the body 1 below the arm 8 by means of the screw 20^a. It may be integral with the head 2, or not, as desired. The ordinary type of iron is shown in Figs. 5 and 6. It has one operating surface 21 which is generally convex about an axis substantially perpendicular to the tread face of the sole 21^a and is shaped about a horizontal axis so as to conform to the desired shape of sole edge. It is often desired to form ridges 22,

23 at the top and bottom of the sole edge, respectively. Corresponding indentations are therefore formed on the face of the setting iron. In the ordinary type of iron the overhang 26 of the upper indentation 24 is cut away at its central portion 27 in order to place the indenting wheel low enough to indent the welt properly. The removal of the ridge forming surface at its center, which is the point of maximum pressure, causes the upper ridge to be formed by the portions of the iron as each side of the point of maximum pressure, and the best ridge forming effect is not obtained, see 28; Fig. 6.

In the improved form of iron, shown in Figs. 3, 4, 7 and 8, the face of the setting iron has two convexities, 29, 30 about axes substantially perpendicular to the tread face of the sole 21^a, located on each side of the median line of the iron. The wheel 18 is mounted directly above the depression 31 between these convexities or "humps". The cutting away of the central part of the overhang 26 does not affect the performance of the setting surfaces 29, 30, since they extend above the cutaway portion 27 sufficiently at 32, 33 to give the best edge setting effect.

Having described our invention, what we claim as new and desire to protect by United States Letters Patent is:—

1. A device of the character described, comprising a holder, an indenting wheel carrier mounted in said holder for motion substantially parallel to the tread face of a shoe sole, and a hinge connection between said holder and said carrier.

2. A combined edge setting and indenting tool comprising a holder, an indenting wheel carrier slidably carried by said holder, a thrust pin connecting said carrier and said holder, and an edge setting iron carried by said holder.

3. A device of the class described comprising a holder, an indenting wheel carrier mounted to slide loosely on said holder, and pivoted stress-taking members mounted between said carrier and said holder.

4. A combined edge setting and indenting device comprising a holder, an indenting wheel carrier in slidable connection with said holder, said connection comprising oscillating stress-taking members, and an edge setting iron adjacent to said carrier.

5. A combined edge setting and indenting device comprising a holder, an indenting wheel carrier mounted in said holder, opposed bearings on said holder and indenting wheel carrier, stress-taking members mounted in said bearings, and an edge setting iron mounted on said holder.

6. The combination of an edge setting iron, an indenting wheel and a carrier therefor in slidable connection with said iron, and stress-taking members in connection

with said carrier, substantially perpendicular to the surface of the work operatively presented to said indenting wheel.

7. A device of the character described comprising a holder, an indenting wheel carrier in loose movable connection therewith, and an oscillatory support between said holder and said carrier.

8. The combination of an edge setting iron with an indenting wheel carrier, and a rotatable stress-taking member supporting said carrier against the stress exerted by the work being indented.

9. The combination of an edge setting iron with a holder, an indenting wheel and a carrier therefor in slidable connection with said holder, and stress-taking members extending between said carrier and said holder substantially in the direction of the stress exerted upon said wheel by the work presented thereto.

10. A device of the class described, comprising a holder, an indenting wheel carrier loosely mounted in said holder, and stress-taking members extending between said holder and said carrier, substantially in the direction of the reaction between said holder and said carrier.

11. A combined edge setting and indenting device comprising an iron having a plurality of operating surfaces and an indenting wheel mounted between said surfaces.

12. A combined edge setting and indenting device comprising an iron having an operating surface with a transverse depression therein, and an indenting wheel mounted opposite said depression.

13. A combined edge setting and indenting device comprising an iron having an operating surface with a depression therein substantially perpendicular to the tread face of a sole when said sole is presented in operative relation thereto, and an indenting wheel mounted in alinement with said depression.

14. A combined edge setting and indenting device comprising an iron having an

operating surface containing a recess, a groove extending from said recess across the operating surface of the iron, and an indenting wheel mounted opposite said recess.

15. A combined edge setting and indenting device comprising an iron having an operating surface with a depression therein, and having a groove crossing said depression, and an indenting wheel so constructed and arranged that its operating face lies closer to said groove where it crosses said depression than elsewhere.

16. A combined edge setting and indenting device comprising an iron having a plurality of operating surfaces, and having a groove extending across said surfaces, and an indenting wheel extending substantially to said groove at a point between said surfaces.

17. A combined edge setting and indenting device comprising an iron having two convex operating surfaces having a depression between them, a groove running across said surfaces in their upper portions, said iron being cut away in the neighborhood of said depression, substantially to said groove, and an indenting wheel mounted in said cut away portion of said iron.

18. A combined edge setting and indenting device, comprising an iron having two operating surfaces, and cut away in its upper portion between said surfaces to a point below the upper operative portion of said surfaces, and an indenting wheel mounted in said cut-away portion.

19. An indenting wheel carrier and a rotatable, incompressible thrust-taking member supporting said carrier.

In testimony whereof we have signed our names to this specification in the presence of two subscribing witnesses.
